IRONER

George W. Wardwell, Jr., Nichols, Conn., assignor to General Electric Company, a corporation of New York

Application February 18, 1936, Serial No. 64,480

2 Claims. (Cl. 38—60)

The present invention relates to ironers of the type in which ironing is effected between a heated shoe and a padded roll.

The object of my invention is to provide an improved construction and arrangement in ironers of this type, and for a consideration of what I believe to be novel and my invention attention is directed to the accompanying description and the claims appended thereto.

In the accompanying drawing, Fig. 1 is a side elevation partly broken away of an ironer embodying my invention; Fig. 2 is an end elevation of the ironer; Fig. 3 is a sectional view taken on line 3—3 of Fig. 2; Fig. 4 is a fragmentary sectional view taken through the shoe and the pressure applying mechanism for the shoe; and Fig. 5 is a fragmentary view showing a modification of my invention.

Referring to the drawing, the numeral 1 indicates the ironer frame or housing having a depending sleeve 2 which fits over the upper end of the wringer post 3 of a domestic washing machine A. The lower end of the sleeve 2 is provided with a flange 4 which rests on a collar 5 secured to the wringer post. Rotation of the ironer housing relative to the wringer post is prevented by a tongue 6 on the flange 4 which fits into one of a number of spaced holes 7 in the collar 5. The ironer can therefore occupy different angular positions with respect to the wringer post. Extending through the wringer post is a wringer drive shaft 8 which is rotated continuously in one direction by the driving mechanism of the washing machine. On the upper end of the wringer shaft is threaded a beveled gear 9 which meshes with a crown gear 10 fixed to a shaft 11 journaled in the side walls of the ironer housing. Fixed in a boss 12 of the housing is a tubular arm 13 which supports the ironer roll 14. The roll 14 comprises a cylindrical metal shell 15 having suitable padding 16 held on its outer surface by a pad cover 17. Within each end of the shell 15 is a disc 18 having a flange 19 secured to the shell. At the center of each disc is fixed a tube 20 carrying a sleeve bearing 21 which rotatably supports the roll on a sleeve 22. Endwise movement of the roll 14 on the roll supporting tube 13 is prevented by washers 22a. Each of the sleeves 22 is prevented from turning on the tube 13 by means of a pin 23 which extends through the tube. One end of the pin 23 rests in a socket 24 on the inner side of the sleeve 22 and the other end of the pin extends through a hole 25 in the sleeve. Viewed in Fig. 3, each of the sleeves 22 is normally biased upward against the lower edge

of the roll supporting tube 13 by means of a coil spring 26 which surrounds the pin 23 and which is arranged between a cup 27 fixed in the tube and a cup 28 on a sleeve 29 slidably carried in the tube. The upper end of the sleeve 29 bears against the inner surface of the sleeve 22 and transmits the force of the coil spring 26 to the sleeve, thereby moving the sleeve 22 upward until it strikes the lower surface of the tube 13. Under this condition, a ring gear 30 which is carried by the disc 18 adjacent the ironer housing 1 is out of engagement with a pinion 31 which is formed in the left end of the shaft 11 and the rotation of the shaft 11 by means of the gears 9 and 10 does not cause rotation of the roll. When the shoe 32 is pressed against the roll the pressure exerted by the shoe overcomes the force exerted by the relatively light coil springs 26 and moves the roll downward to the position shown in full lines in Fig. 3. In this position the gear 30 meshes with the pinion 31, thereby completing a driving connection from the shaft 11 to the roll and causing rotation of the roll. The gears 30 and 31 therefore function as a clutch which is operated by the pressure between the shoe and the roll to complete a driving connection to the roll. One advantage of this construction is that the gears 30 and 31 engage when the pressure between the roll and the shoe is sufficient to overcome the relatively weak coil springs 26. There is therefore only a relatively small load on the tips of the gear teeth as the gears engage. Also, since the roll starts rotating before the full ironing pressure is developed there is no heavy starting load.

The shoe 32 is carried on an arm 33 which is secured at one end in a boss 34 on the ironer housing and which extends along the roll. The roll contacting surface of the shoe comprises a sheet metal plate 35 having studs 36 secured thereto to which is bolted a sheet metal cover 37. Between the cover 37 and the plate 35 are arranged suitable electric heating elements (not shown). At the center of the shoe is a supporting bracket 38 which is secured to a plate 39 carried on the underside of the cover 37 on two of the studs 36. Between the ears 40 of the bracket 38 is a U-shaped link 41 which is pivotally connected thereto by means of a pin 42. The ends of the U-shaped link 41 are pivoted on the arm 33. The link 41 and the bracket 38 form a toggle for pressing the shoe against the roll. The toggle is operated by means of a lever 43 which is pivoted to the arm 33, as shown in Fig. 4, and is also connected to the pin 42. The lever 43 is cen-

tered between sides of link 41 by means of spacing sleeves 44 and 45. It is apparent that the lever 43 is in effect a part of the link 41. The lever 43 projects over the center of the ironer roll and is therefore accessible to either hand of the operator. When the lever 43 is rotated in a counter-clockwise direction, as viewed in Fig. 4, the shoe is moved to the full line position shown in Fig. 4. In this position the pin 42 is moved past the center line connecting the center of the roll and the center of the arm 33 so that the shoe tends to remain in this position. A pin 48 fixed to the arm 33 engages the edge 54 of the lever 43, limiting the movement of the lever. When the shoe is pressed against the roll, the roll is moved parallel to its axis of rotation from its normal position to the position shown in full lines in Fig. 4, completing the driving connection to the roll which causes the roll to rotate in a clockwise direction, as viewed in Fig. 4. When the shoe first contacts the roll the pin 42 is above the center line connecting the roll and the arm 33. At this time the roll starts rotating and the frictional torque exerted on the shoe by the roll tends to straighten the toggle and move the shoe to the full line position shown in Fig. 4. The frictional torque thus decreases the effort required to move the shoe to the ironing position. The frictional torque assists in pressing the shoe against the roll because the arm 33 about which the shoe is moved is located outside the line of action of the frictional force exerted on the shoe by the roll.

During the use of the ironer, varied thicknesses of material may be placed between the shoe and the roll and also padding on the roll may vary in thickness. It is therefore desirable to provide some means for equalizing the pressure between the roll and the shoe under these varying operating conditions. This is accomplished by making the arm 33 of sufficient resilience so that it equalizes the pressure between the roll and the shoe. This construction is simpler than constructions which use separate springs to equalize the pressure between the roll and the shoe.

When the operating lever 43 is moved in a clockwise direction, as viewed in Fig. 4, the pin 42 is moved to the upper side of the center line between the roll and the arm 33 and a coil spring 46 arranged between the link 41 and a pin 47 fixed to arm 33 returns the shoe to the dotted line position shown in Fig. 4. The pin 48 which is fixed to the arm 33 engages the edge 49 of the lever 43 and provides a stop for limiting this movement of the operating lever. When the shoe is in the dotted line position it may be pivoted upward about pin 42 so that the roll contacting surface of the shoe is readily accessible for cleaning.

Under some conditions it is desirable that the ironer be used merely as a press. To permit this use of the ironer, I have provided a slide 50 which is located on the side of the tube 13 facing the shoe. At its right end slide 50 is held by a screw 51 which extends through a slot 52 in the slide and at its left end by the sleeve 22 and a pin 23 which extends through a slot 55 in the slide. The right hand end of slide 50 carries a block 53 which may be moved between the roll supporting tube 13 and the sleeve 22 adjacent the wringer housing 1, thereby holding the gear 30 out of engagement with the pinion 31 when the shoe is pressed against the roll. This prevents completion of the driving connection to the roll and

enables the ironer to be used as a press. On the left hand end of slide 50 is a handle 59a which projects beyond the end of the roll and may be used for moving the slide back and forth along tube 13.

In the modification shown in Fig. 5, friction ring gear 30a and gear 31a replace the toothed ring gear 30 and gear 31. There are no other changes in construction.

10 In the use of the ironer, the material to be ironed is arranged on the roll beneath the shoe. The lever 43 is then pulled toward the operator thereby pressing the shoe against the roll. When the pressure between the roll and the shoe overcomes the springs 26, the shoe is moved transversely to its axis of rotation moving the gear 30 which is carried by the roll into engagement with the pinion 31. This completes the driving connection to the roll, and the rotation of the roll 15 draws the material under the shoe. By this arrangement the roll remains stationary until contacted by the shoe but starts to rotate before full ironing pressure is reached. This prevents heavy starting loads. At the completion of the ironing operation, the lever 43 is moved away from the operator moving the shoe out of pressing engagement with the roll. As pressure is released, the roll is moved by springs 26 parallel to its axis of rotation to a position in which the gear 30 is out 20 of mesh with the pinion 31 thereby breaking the driving connection to the roll.

What I claim as new and desire to secure by Letters Patent of the United States, is:

1. An ironer, a roll, a frame at one end of the 35 roll having means supporting the roll for rotation on its axis, a shoe supporting arm having an angle bend intermediate its ends, one end of the arm being fixed to the frame and extending transverse to the axis of the roll and the other 40 end of the arm extending along the roll at an angle to said first end, a shoe supported on said other end of the arm, and a toggle having a link carried by a bearing on said other end of the arm for moving the shoe toward and away from the roll, said link being pivoted on the longitudinal axis of said other end of the arm, and said arm being sufficiently resilient to equalize the pressure between the roll and the shoe under varying operating conditions.

2. In an ironer, a roll, a shoe, a frame at one end of the roll having provisions for supporting the roll, an arm projecting from said frame along the roll, a toggle for moving the shoe toward and away from the roll comprising a pair of links pivoted to each other, one of said links being carried on the projecting part of said arm and the other being fixed to the shoe, means for pivoting the first link about the axis of said arm to straighten or break said toggle whereby the shoe is moved 55 toward and away from the roll, the common pivot of said links lying substantially on a center line connecting the arm and the roll when the shoe is pressed against the roll, driving means for rotating the roll in a direction such that the friction torque exerted by the roll on the shoe tends to straighten the toggle, and means operated by movement of the toggle for controlling said driving mechanism to stop the roll when the shoe is away from the roll and to start rotation of the roll prior to the development of full pressure between the roll and shoe.
